PIPE REST

Arthur A. Villarreal, 3568 Shurtleff Court,
Los Angeles, Calif. 90065

Continuation-in-part of abandoned design application Ser.
No. 394,743, Sept. 6, 1973. This application Feb. 27,
1975, Ser. No. 553,571

Term of patent 14 years

Int. Cl. D27—99

U.S. Cl. D27—6

Fig. 1.

Fig. 2.

Fig. 3.

Fig. 4.

Fig. 5.

Fig. 6.

FIG. 1 is a front elevational view of a pipe rest showing my new design;

FIG. 2 is a right side elevational view thereof;

FIG. 3 is a top plan view thereof;

FIG. 4 is a left side elevational view thereof;

FIG. 5 is a back elevational view thereof; and

FIG. 6 is a bottom plan view thereof.

This is a continuation-in-part of design application Ser. No. 394,743, filed Sept. 6, 1973, and now abandoned.

I claim:

The ornamental design for a pipe rest, substantially as shown.
